UNITED STATES PATENT OFFICE

WARD I. HUBER AND LOWELL B. CLOSE, OF CLEVELAND, OHIO, ASSIGNORS TO W. I. HUBER, INC., OF CLEVELAND, OHIO, A CORPORATION OF OHIO

SPHYGMOMANOMETER

Application filed December 12, 1929. Serial No. 413,567.

Our invention relates to an improvement in sphygmomanometers, and our purpose in general is to provide a small mercury instrument adapted to apply pressure in a small 5 spot like area over an artery until it is so compressed that the flow of blood is stopped entirely or persists only during a part of the cycle, the pressure of the blood in the artery being indicated in terms of the height in 10 millimeters of a mercury column. The instrument is of small dimensions and includes a graduated pressure indicating tube having a compressible member at its bottom whereby 15 an artery may be compressed and a body of mercury simultaneously displaced and quantitatively transmitted instantaneously to the tube. The instrument is also particularly constructed to permit oscillation of the mercury without building up an internal air pressure 20 sure, and to promote readings of systolic or diastolic pressure, while sealing the mercury at all times against exposure to the atmosphere. For such purposes we use a collapsible air bag of greater capacity than the 25 receiving bore for the mercury column, which bag is extremely sensitive to the movement of the mercury within the column and offers no resistance to its rise or fall to any height or elevation therein. The instrument is also 30 particularly designed to facilitate its production and assembly, to give accessibility to its parts, and to permit convenient inspection, tests, replacements and repairs, all as herein-after more fully explained.

35 In the accompanying drawing, Fig. 1 is a cross-sectional view taken on line 1—1 of Fig. 2, and Fig. 2 a side view of the sphygmomanometer with its shield rotated to an open position, Fig. 3 is a cross sectional 40 view on line 3—3 of Fig. 4 and Fig. 4 a side view of the sphygmomanometer with the shield closed. Fig. 5 is a front view of the instrument open. Fig. 6 is a sectional view longitudinally of the instrument. Figs. 7 45 and 8 are sectional and perspective views, respectively, of the closure cap and collapsible bag separator, and Fig. 9 is a side elevation of the same parts united together. Fig. 10 is a sectional view of the air displacement cylinder used at the top of the instrument, and

Figs. 11, 12 and 13 are perspective views of the upper sealing band, the glass column, and the lower gasket, respectively. Fig. 14 is a bottom view and Fig. 15 a cross sectional view taken on line 15—15 of Fig. 4 of the 55 pressure applicator used at the bottom of the instrument.

The sphygmomanometer comprises a barrel 2 made of metal or a hard composition, the upper end of which is screw-threaded internally to receive the reduced screw-threaded neck 3 of a short cylinder 4 having an air chamber 5 therein, including a central opening 6 in its bottom. An elongated rubber bag 7 having a thin distensible and collapsible wall is suspended within chamber 5 from a flanged cap 8 having screw connection with the upper end of cylinder 4. The bag is secured at its upper end, which is open, to the cap by a stiff ring 9 which is of sufficient diameter to compress the rubber edge of the bag with binding and sealing effect against the screw flange of the cap. However, an inclined passage 10 in the top of cap 8 provides constant open communication between the interior of bag 7 and the atmosphere, thereby permitting the bag to collapse without restraint. The wall of the bag is also so thin and flexible that no inherent tension of any consequence hinders the buckling of the bag inwardly when air is forced through opening 6 into air chamber 5. This occurs when a column of mercury 11 is forced upwardly in a bore 12 of relatively small diameter in a glass tube 14 attached to neck 3 of cylinder 4. A rubber band 15 encircles the upper end of the glass tube within neck 3 to cushion and protect the glass and to provide an air and liquid seal, and the lower portion of the glass tube is also secured and sealed in like manner by a larger rubber band or gasket 16 where it is pressed into an annular channel at the bottom of a cylindrical enlargement 17 on barrel 2, see Fig. 6. The lower end of the glass tube is also enlarged and provided with a larger bore or well 18 within which a short column of mercury stands at a predetermined level when the instrument is not in use. The main body of mercury M is confined within a rubber boot or 100

pressure applicator 19 having relatively thick side walls 20 and a thin flexible bottom 21. The upper end of applicator 19 is open and circular and the wall reduced in thickness to 5 permit it to be sleeved over the cylindrical enlargement 17 on barrel 2 where it may be screw-engaged and compressed tightly against enlargement 17 by a rotatable collar 22. The reduction in thickness of the upper 10 wall of the applicator or boot provides an annular shoulder 23 internally which is engaged by the bottom edge of the barrel and takes the thrust of the instrument when it is pressed downwardly to constrict an artery. 15 A direct pressure is applied through the rubber boot and there is very little surrender or yield in the thick walls of the boot, especially the two side walls which extend on straight parallel lines the full length of the 20 boot to bottom 21 see Fig. 5. The boot is also formed in part with flaring walls to provide a bottom 21 approximately twice as long as it is wide, and this elongated bottom is thin and elastic although slack and not under tension 25 when not distended by the weight of the mercury. Thus, when the instrument is suspended apart from a place of rest, bottom 21 bulges downwardly and is stretched in some degree by the weight of the mercury, but 30 when the instrument is permitted to settle upon a supporting surface the bottom will flatten out until it is slack and free to flex within limits without tension. The column of mercury may thus be placed at rest in a 35 localized area over an artery and the walls of the artery compressed at two places where the thick walls of the boot engage the surface, then the pressure of the instrument may be directly utilized in overcoming the pressure 40 of the blood in the artery, allowance being made in calibrating the instrument for the slight resistance offered by the small area involving the tissues of the arm and the walls 45 of the artery, and any variation in the capillary action of the mercury.

The fluctuations in pressure are transmitted instantaneously to the mercury and the oscillations may be watched through the glass tube to determine the points of systolic 50 or diastolic pressure, readings being obtained by a scale 24 in millimeters of mercury. Scale 24 consists of a piece of celluloid or other transparent material partly circular to conform to and fit within the circum- 55 lar wall of barrel 2, and partly flat or substantially flat to span the open side of barrel 2 and to bring the graduated markings close to the glass tube. The lower end of this celluloid piece 24 is circular and fits snugly 60 within the enlarged part 17 of the barrel where it is seated upon the rubber band or gasket 16. A rotatable sleeve 25 encases barrel 2, one side being open for part of its length to expose the transparent scale when 65 given one half of a turn relatively to the

barrel. A pin 26 in one side of barrel 2 co-acts with the end walls of a semi-circular slot 27 in sleeve 25 to limit the rotatable movements of the sleeve, which rotative movement may be easily effected by gripping a knurled enlargement 28 at the upper end of the sleeve where it overlaps the sides and abuts against the bottom of cylinder 4. When this cylinder or head piece is unscrewed from barrel 2, the sleeve 25 and other parts may be readily separated, but when all the parts are firmly connected together the mercury is sealed at all points and can not escape inasmuch as the boot closes the bottom and the air bag 7 seals the top of the tube. 70 On the other hand the air confined within the glass tube is easily transferred to air chamber 5 within cylinder head 4 without compression and no resistance is offered to the upward movement of the mercury, inasmuch as bag 7 has a greater air capacity than the bore in the mercury tube and because the circular walls of the bag are thin and of sufficient area to buckle-in very freely. In addition continuous sealing by air bag 7 prevents loss of mercury, exposure of the mercury to the atmosphere, darkening of the instrument by oxidation, and intake of dirt. 75

What we claim is:

1. A sphygmomanometer, comprising a 85 transparent tube having a mercury container connected therewith, the bottom of said container being yieldable to effect displacement and uplift of the mercury and the border edge of said container being yieldably re- 90 sistant to thrust to effect compression of an artery in a circumscribed area, and a flex- 95 ible air bag suspended above the top of the tube and sealing the same against the open atmosphere. 100

2. A sphygmomanometer, comprising a tubular column having an enlarged bore in its base portion, a yieldable artery constrict- 110 ion device containing a liquid and provided with a sensitive vibratory diaphragm adapt- 115 ed to displace the liquid and transmit the pulsations of an artery to the liquid forced into said column, a detachable hollow mem- 120 ber open to the upper end of said tube and a thin flexible bag open internally to the at- 125 mosphere and suspended therein for sealing the tube against the open atmosphere.

3. A sphygmomanometer, comprising a transparent tube with measuring indicia lengthwise of said tube, a yieldable boot at 120 the bottom of said tube having a portion thereof adapted to yieldingly apply a constricting pressure to an artery and another portion to vibrate with the pulsations of the artery while it is being constricted, said 125 boot containing a liquid adapted to be dis- placed by the movements of both portions thereof, a cylinder having an air chamber open to the upper end of said tube, and a 130 detachable cap for said cylinder having a

collapsible bag suspended therefrom and displacing air within said chamber, the interior of said bag being open to the atmosphere.

- 5 4. A sphygmomanometer, comprising a transparent vertical tube, a chamber at its bottom having a slightly yieldable circumferential side wall and a more readily yield-
ing bottom, and a collapsible device for seal-
10 ing the upper part of said tube, said circum-
ferential side wall being adapted to con-
strict a blood vessel at two distinct places,
when said chamber is pressed downwardly
upon such blood vessel.
- 15 5. A sphygmomanometer, comprising a transparent tube, a mercury filled yielding boot therefor having a thin yielding bottom and a circumferential integral side wall of
20 greater wall thickness and less yield than
said yielding bottom, a hollow head for said tube and a flexible air displacement bag within
in said head communicating with the at-
mosphere and sealing the upper part of the
tube from the atmosphere.
- 25 6. A sphygmomanometer, comprising a vertical transparent tube, a compressible member attached to the bottom of said tube, said member including an integral circum-
ferential side wall of less yielding properties
30 than the freely yielding bottom of said mem-
ber, to permit constriction of an artery at
two distinct places when said sphygmoman-
ometer is forced downwardly upon said
artery, said tube containing a liquid element
35 exposed to and constantly subject to the
movements of said compressible member, an
air chamber at the top of said tube and a col-
lapsible air bag within said chamber and
for sealing same against the open atmosphere,
40 the air capacity of said bag being at least
equal to the air space within the tube.

7. A sphygmomanometer, comprising a slotted barrel, a slotted sleeve rotatably mounted upon said barrel, a transparent tube
45 within said barrel, a graduated scale within
said barrel opposite said tube, a boot filled
with mercury connected with said barrel and
communicating with said tube and having a
thin bottom and provided with side walls
50 adapted to compress a blood vessel and sim-
ultaneously force a portion of the mercury in
said boot upwardly into said tube, a hollow
head detachably connected to the upper end
of said barrel and serving as a retaining
55 member for said sleeve, and collapsible seal-
ing means for said tube connected to said
head.

8. A sphygmomanometer, comprising a transparent tube containing mercury, a trans-
60 parent scale sleeved over said tube, a yield-
able boot at the bottom of said tube adapted
to compress an artery and transmit a pulsat-
ing movement of the artery upwardly to the
mercury in the column, a hollow head for
65 said tube, a barrel connecting said boot and

head, sealing gaskets between said tube and
head and said tube and barrel, a cap member
for said head having an air opening therein,
and a flexible bag suspended from said cap
member and sealing the upper part of the
70 tube from the atmosphere.

In testimony whereof we affix our signa-
tures.
